MATTRESS HANDLE PRESS

Clayton S. Spinney, Greenland, N.H., assignor to The Morley Company, Portsmouth, N.H., a corporation of Maine

Filed June 13, 1961, Ser. No. 116,846

13 Claims. (Cl. 1—318)

This invention relates to presses and more particularly to a press for automatically attaching handles to fabric materials.

It is conventional to place around the periphery of a mattress handles by which the mattress may be moved and turned. These handles are typically applied directly to the strip of fabric which forms the sides of the mattress. It is thus a primary object of the present invention to provide apparatus for applying handles to such material quickly and cheaply and with as little human supervision as possible.

Further objects are to provide such apparatus which is largely automatic, which is highly reliable, which forms a very secure attachment between handle and fabric, which is not subject to rapid wear, which is easily adjusted and repaired, which is compact, and which is relatively inexpensive.

In achieving these objects the invention contemplates a press which will apply handles having pre-attached pronged fasteners of the type in which the prongs are adapted to engage a locking ring. The press has a reciprocating head which forces the prongs of the fastener through the fabric and into a closing die which turns the prongs. In a preferred embodiment a plurality of closing dies are provided and are spaced around a disk which is rotated so as to bring successive dies into position below the head. Preferably there is provided means for automatically loading locking rings into the closing dies as the disk rotates. Preferably also there is provided a means for feeding handles successively into the reciprocating path of the head so that the head with each stroke carries a handle into engagement with the fabric.

For purposes of illustration a preferred embodiment of the invention is shown in the accompanying drawings in which

FIG. 1 is a top view of a handle attaching press;

FIG. 2 is a front view of the press;

FIG. 3 is a side view of the press;

FIG. 4 is a side view of a prong fastener;

FIG. 5 is a section on the line 5—5 of FIG. 2;

FIG. 6 is a section on the line 6—6 of FIG. 5;

FIG. 7 is a section on the line 7—7 of FIG. 2;

FIG. 8 is a section on the line 8—8 of FIG. 3;

FIG. 9 is similar to FIG. 8 with the head being shown in its lower position;

FIG. 10 is a view similar to FIG. 9 in section and to a larger scale;

FIG. 11 is a back view of a piece of fabric with a pronged fastener and locking ring attached; and

FIG. 12 is a schematic representation of the pneumatic control system for the press.

Referring now to FIGS. 1, 2 and 3, the press is built around a frame 10 which includes a top cantilevered portion 12 and a bed 14. The space between the portion 12 and the bed 14 constitutes a path for a strip of fabric material 16 (shown in dot-dash lines) to which handles are to be applied. In the portion 12 of the frame there is journaled a head 20 which includes a pair of spaced driving dies 22. The head 20 is adapted to be driven downwardly by a toggle linkage 24 whose upper end is pivoted to the frame 10 and whose lower end is pivoted to the head 20. The height of the upper pivot 26 may be adjusted by means of the bolts 28 and the lock nuts

2

30 so that the lowermost position of the head 20 may be correspondingly adjusted. For straightening the toggle linkage 24 and thus driving the head 20 downwardly, there is provided a pneumatic cylinder 32 whose one end 5 is pivotally connected to the frame 10 by the arm 34 and whose piston 36 is connected to the central or swing ing pivot 38 of the toggle linkage 24.

For the handles to be applied, there is provided an arched guideway 40 (FIG. 3) whose upper end extends 10 over the press so that handles may be easily loaded into the apparatus from the front of the press and thence conducted by gravity to the reciprocating head 20. The handles 42 (FIGS. 7 and 8) are provided with pre-attached pronged fasteners 44 which, as may be seen in 15 FIG. 4, include a plurality of pointed prongs 46. These prongs fit in corresponding slots in the ends of the handle (FIGS. 8 and 10) and, before attachment to the fabric strip, are held there by friction. After proceeding down the guideway 40 the handles 42 arrive at a positioner 50 (FIGS. 7, 8 and 9) which is attached to the frame 10 and which includes the pair of pivoted arms 52 which are biased by the spring 54 to hold the leading handle in the path of the reciprocating head 20. The arms 52 hold the handle by tapered edges 56 so that, as the head 25 20 comes down and the driving dies 22 engage the correspondingly spaced fasteners 44, the handle is taken from the positioner 50 and carried down into engagement with the fabric 16. To prevent the possible bowing of the handles the head 20 is provided with a spring loaded pin 30 59 which bears lightly against the central portion of each handle 42 as it is fastened to the fabric strip.

On the opposite side of the fabric 16 and positioned by means to be explained hereinafter, there is a closing die 60 (FIG. 10). Resting in this die, is a locking ring 62. 35 As the driving dies 22 continue downwardly the prongs 46 of the fastener 44 are driven through the fabric and are turned outwardly by engagement with the closing die 60 so as to engage and lock with the locking ring 62 in the manner shown in FIGS. 10 and 11. Preferably, there 40 is provided concentric with the driving die 22 and fastened to the head 20 by the same screw 23, a permanent magnet 19 for holding the fasteners 44 in proper alignment with the dies 22 in the interval between leaving the positioner 50 and engaging the fabric 16.

45 So that the locking rings 62 may be automatically provided as needed, the press includes a plurality of closing dies 60 which are spaced around the peripheries of a pair of disks 65 which may be rotated so as to bring successive locking dies 60 into position under the respective driving dies 22. The disks 65 are set into the bed 14 of the press so as to provide a firm support for the fastener closing action. At a portion of each disk removed from the operating position, there is provided a locking ring tube 67 (FIGS. 1 and 2) which is adapted 50 to drop a single locking ring into each empty closing die 60 as it passes by the tube.

60 For rotating the disk 65 there is provided a second pneumatic cylinder 70 (FIGS. 5 and 6) which is adapted to move the levers 72, 74 and 76 so as to rotate the ratchet drive 78 which in turn unidirectionally rotates the disks 65. An adjustable stop 79 limits the extent of this movement. The exact positioning of each disk 65 for the proper making of the fasteners 44 and the locking rings 62 is accomplished by an indexing pin 80 (FIG. 65 1) which is urged into engagement with corresponding indentations 82 on the disks 65 by the spring 84.

70 Control of the press is achieved by means of the pneumatic switch 86. With the switch lever 86 in its raised or normal position, compressed air is conducted, by the piping shown schematically in FIG. 12, to the side of the cylinder 32 such that the head 20 is held in its raised posi-

tion. Likewise air is provided to the cylinder 70 so that its piston 71 is extended. When the operator has properly positioned the fabric 16, the switch lever 86 is depressed and air is provided to the opposite sides respectively of the cylinders 32 and 70. This causes the cylinder 32 to straighten the toggle linkage 24 thereby driving the head 20 downwardly so as to pick up a handle 42 and drive the prongs 46 of its corresponding fasteners 44 into engagement with a waiting locking ring 62. At the same time, piston 71 of the cylinder 70 will be withdrawn; however, this will not rotate the disk 65 as this rotation is opposite that transmitted by the ratchet drive 78. When the securing of the handle is completed, the switch lever 86 is released and the head 20 is withdrawn by the cylinder 32. Again simultaneously air is provided to the cylinder 70 causing the drive 78 to be rotated in a counterclockwise direction as seen in FIG. 5. This rotation will bring another closing die 60 carrying a locking ring 62 into position under each driving die 22 and thus the cycle is ready to begin again.

In the preferred embodiment there is also provided, though not shown in the other views for purposes of clarity, a plurality of air jets 88 and 90. The jets 88 are oriented so as to provide a force urging the next handle 42 in the guide 40 into the positioner 50. This force is in addition to the gravitational force exerted by any other handles in the guide and helps to overcome the resilience of the spring 54. The jets 90 are oriented adjacent the disks 65 so as to empty each closing die 60 just before that die passes beneath the loading tube 67 thereby to avoid jamming of the apparatus if a fastener fails to properly engage its locking ring.

It should be understood that this disclosure is for the purpose of illustration only and that the present invention includes all modifications and equivalents falling within the scope of the appended claims.

I claim:

1. For applying to a strip elongate handles having pre-attached pronged fasteners spaced apart a predetermined distance lengthwise of the handles, apparatus comprising a frame having a bed over which the strip may be drawn, a reciprocating head mounted in said frame above the bed with driving dies spaced apart said predetermined distance, means including a plurality of fastener-closing dies under said dies below the bed for positioning fastener closures, and means for guiding handles over the bed to a position in which said fasteners are between said driving and closing dies respectively.

2. For applying to a strip elongate handles having pre-attached pronged fasteners spaced apart a predetermined distance lengthwise of the handles, apparatus comprising a frame having a bed over which the strip may be drawn, a reciprocating head mounted in said frame above the bed with driving dies spaced apart in one direction said predetermined distance, means including a plurality of fastener-closing dies under said dies below the bed for positioning fastener closures, and means for guiding said handles over the bed transversely to said direction to a position in which said fasteners are between said driving and closing dies respectively.

3. Apparatus according to claim 2 wherein said last means includes spaced guides engaging the ends of the elongate handles.

4. Apparatus for applying handles having two pre-attached pronged fasteners to a fabric strip comprising a frame having a bed over which a fabric strip may be drawn, a reciprocable head journaled in said frame above the bed and having a pair of spaced driving dies, means for guiding handles into the path of said head above the bed with the fasteners positioned beneath said driving dies, a pair of discs set into said bed beneath said head, each of which discs has on one face thereof and equally spaced around its periphery a plurality of fastener closing dies, and means, on the opposite side of each disc from said head, for loading fastener closing rings into said closing dies.

5. Apparatus according to claim 4 and further comprising: a manual switch, means, responsive to the movement of said switch in one direction, for driving said head through a fastener closing stroke; and means, responsive to the movement of the switch in the other direction, for causing each of said discs to advance another closing die into position under said head.

6. Apparatus according to claim 4, and further comprising a toggle link for reciprocating said head and an air cylinder for driving said toggle link at its middle pivot.

7. Apparatus according to claim 4, in which the means for guiding handles includes an arcuate handle guide which arches from over said frame to the path of said head whereby handles may be gravity fed into the path of said driving dies.

8. Apparatus according to claim 7, and further comprising positioning means for resiliently holding a handle in said path so that the driving dies can engage the handle and carry it to a fabric strip lying over said closing die.

9. Apparatus according to claim 8 and further comprising air jet means for urging a handle from said guide into said positioning means.

10. Apparatus according to claim 9, and further comprising indexing means for causing each of said discs to be releasably held with one of said closing dies located precisely under one of said driving dies except when said discs are being rotated.

11. Apparatus according to claim 4, and further comprising means for rotating each of said discs between reciprocations of said head.

12. Apparatus according to claim 11, in which the means for loading fastener closing rings is a gravity supply tube.

13. Apparatus according to claim 11, and further comprising air jet means for emptying each closing die just before it passes under said closing ring supply tube.
